UNITED STATES PATENT OFFICE.

JOHN BLACK, OF MONACA, PENNSYLVANIA.

CARD OR TICKET HOLDER.

No. 895,333.

Specification of Letters Patent.

Patented Aug. 4, 1908.

Application filed November 16, 1907. Serial No. 402,382.

To all whom it may concern:

Be it known that I, JOHN BLACK, a citizen of the United States of America, residing at Monaca, in the county of Beaver and State of Pennsylvania, have invented certain new and useful Improvements in Card or Ticket Holders, of which the following is a specification, reference being had therein to the accompanying drawing.

10 This invention relates to card or ticket holders especially designed for use upon railway freight cars.

The primary object of the invention is, to provide simple and inexpensive means for 15 clamping a card ticket or label to the door or side of a car in such a manner as to permit the card ticket or label to be readily removed.

The invention comprises a spring clip of novel form, in combination with means for 20 securing it in position and permitting of its expansion and contraction.

The invention also consists of a spring clip of novel form in combination with a cleat serving as a support for the lower edge of the 25 card or label.

The construction of the improvement will be fully described hereinafter, in connection with the accompanying drawing which forms a part of this specification, and its features of 30 novelty will be set forth in the appended claims.

In the drawing:—Figure 1 is an elevation of the improved holder applied to the side of a car, or to a board or frame secured to the 35 car. Fig. 2 is a horizontal section of the same, and, Fig. 3 is a central vertical section thereof.

The reference numeral 1 designates a support to which the holder is applied, and 40 which may be either the side of a car, or a separate board or panel secured to the car.

Two parallel vertically-disposed keepers 2 are secured to the support 1 by screws 3, each of said keepers consisting of a metallic 45 strap having a central offset 4 through which extends the ends of a spring-clip 5, said ends being bent inward to provide spring loops 6 and having their extremities 7 resting upon the offset portions 4 of the 50 keepers.

The clip 5 is formed with a central loop or bend 8 serving as a finger piece for drawing the clip away from the support 1 to permit of the insertion of a card or label 9 behind it.

Centrally below the finger-piece 8 of the 55 clip a bracket 10 preferably of triangular form is secured to the support 1, the upper edge of said bracket being bent outward and then upward to provide a cleat 11 to support the lower edge of the card or ticket 9.

60 The utility and operation of the improvement will be readily understood. The tendency of the spring loops 6 is to hold the clip 5 against the support 1 thus firmly clamping the card, ticket or label in position. By 65 pulling outward upon the finger-piece 8, the spring-loops 6 yield to permit the clip to be drawn away from the support for the removal or insertion of the card or ticket.

The lower edge of the card or ticket is supported and protected by the cleat 11 as 70 clearly shown in Fig. 3.

It will be apparent that the device may be constructed at small cost, and readily applied to the car or other structure or article.

Having fully described my invention what I claim as new and desire to secure by Letters Patent, is

1. A card or ticket holder comprising parallel keepers, and a spring clip having the 80 ends extending through said keepers, and bent to form resilient loops, and its central portion provided with a finger piece.

2. The combination with a support, of parallel keepers secured thereto and formed with central offsets, and a spring clip having the ends extending through said offsets and bent to provide resilient loops, and its central portion formed with a loop serving as 85 a finger piece.

3. The combination with a support, of parallel vertical keepers secured thereto and formed with central offsets, and a spring clip provided with a central finger piece, and having its ends extending through said keepers 95 and bent to form resilient loops the extremities of which bear against said keepers to adapt said loops to yield when the clip is pulled outward by its finger-piece.

4. The combination with a support of par- 100

allel keepers secured thereto a spring clip supported by said keepers and formed with resilient end loops, and a central finger piece, and a card or ticket support below said 5 clip comprising a bracket provided at its upper edge with a cleat to receive the lower edge of the card or ticket.

In testimony whereof I affix my signature in the presence of two witnesses.

JOHN BLACK.
